UNITED STATES PATENT OFFICE

CHARLES F. RHODES, OF GLENS FALLS, NEW YORK, ASSIGNOR TO INTERNATIONAL PAPER COMPANY, OF NEW YORK, N. Y., A CORPORATION OF NEW YORK

MECHANISM FOR SAMPLING MATERIALS

Application filed July 27, 1929. Serial No. 381,418.

This invention relates to what are known as automatic samplers for taking at periodic intervals, uniform quantities or samples of substances or materials, which samples on being mixed together will give an average of the quality and condition of the material as it existed during the sampling period.

The invention has reference more particularly to an automatic sampler for use in connection with liquids containing matter in suspension, such for instance as the so-called "white water," which flows from the paper making machines usually through a weir or conduit, and which usually holds in suspension such constituents as clay, pulp fiber, and other ingredients, it being desirable for the proper and economic operation of the paper making machine, that the attendant be kept informed as to the nature and amount of the constituents that are passing away from the machine in the "white water," to the end that the proper steps may be taken in the preparation and handling of the stock, and in the adjustment and operation of the machine to prevent undue waste.

In an application for Letters Patent of the United States filed by me on August 10th, 1928, Serial No. 298,823, a sampling mechanism for this purpose is disclosed in which a sampling dipper is constantly revolved by a power operated driving member and at relatively slow speed in such manner as to dip down into the material to be sampled, and then rise therefrom so as to elevate the samples and discharge the same into a suitable receptacle, wherein they are mixed together to be later analyzed.

In the use of such apparatus for sampling liquids containing matter in suspension, such as the "white water" flowing from paper making machines, it has been found that the passage of the sampling dipper through the "white water" at such speed as was contemplated by the mechanism disclosed in said application, would give an opportunity for the fibers and other matters to settle in the dipper to an undue extent, with the result that the samples taken would contain a greater proportion of solid matter

than would be contained in the body of "white water" being sampled, and the mixed samples would not represent as true and accurate an average of the suspended matters as would be desirable.

The present invention is an improvement over that of said application, and has for its object to obtain a more representative and accurate sample of the liquid material with respect to the proportions of the suspended constituents contained therein, and the invention consists in an improved apparatus in which the dipper is accelerated at that part of its revolution where it is immersed in the water to be sampled, with the result that the motion of the dipper through the water will be at such speed as to prevent the matters held in suspension in the liquid from accumulating in the dipper to an undue extent, so that the individual samples will represent more accurately and truly the proportions of solid constituents contained in the liquid at the moment the samples are taken.

In the specification to follow, the improved mechanism will be described in detail and the novel features thereof will be pointed out in the appended claims.

In the drawings:—

Fig. 1 is a plan view of the improved apparatus;

Fig. 2 is a side elevation of the same, and

Fig. 3 is an end elevation looking from the right of Figs. 1 and 2.

Referring to the drawings:

The machine comprises as its chief elements, a driving member 1 adapted in the present instance to be operated by the flow of the liquid material to be sampled, such for instance as the "white water" from a paper making machine; a sampling member or dipper 2 movable down into the flowing water to take a sample thereof, and then upwardly to elevate the same so that the successive samples may be mixed together; and suitable transmitting connections 3 between the driving member and dipper to impart to the latter its periodic movements and to accelerate the speed of the dipper in its passage through the water. These parts are

mounted in and sustained by a suitable rectangular open frame 4 consisting of longitudinal side frame bars 5 and transverse end connecting frame bars 6.

The driving member 1 is in the present instance in the form of a water wheel provided with paddles 7, which wheel is fixed to a horizontal transverse driving shaft 8 rotatably mounted in bearings on the side frame bars, the form and construction of the parts being such that when the frame is set in position over the conduit or weir through which the "white water" flows from the paper making machine, the water wheel will be immersed at its lower side a sufficient depth in the flowing water to be rotated thereby.

Near one end, the driving shaft has fixed to it a bevel pinion 9 meshing with a bevel gear 10 on the end of a longitudinally extending power transmitting shaft 11, which shaft is operatively connected at its opposite end to the dipper 2 in the manner presently to be described, to operate the same. The shaft 11 is extended at its end a short distance beyond the bevel pinion 10, and its extended end is journaled in a bearing opening in a sleeve 12 mounted loosely on the driving shaft and confined thereon by collars 13 pinned to said shaft. The transmitting shaft 11 extends longitudinally at an upward inclination from this point and has fixed to its opposite end a worm 14 engaging a worm wheel 15 eccentrically mounted fixedly on a transverse driven shaft 16 journaled at its ends in outer and inner standards 17 and 18 extending upwardly from the side frame bars. At a point adjacent the worm wheel, the longitudinal frame bar at that side of the machine has fixed to it a standard 19 formed with a guiding slot 20 curved in an arc struck from the axis of the shaft 8 as a center, in which slot is guided a pin 21 projecting laterally from a sleeve 22 loosely surrounding the transmitting shaft 11, which sleeve is confined on the shaft by means of two collars 23 pinned to the shaft. A tension spring 24 is connected at its upper end to the sleeve 23 and at its lower end to the longitudinal frame bar, and tends to draw the transmitting shaft downwardly and thereby maintain the worm in mesh with the worm wheel, while permitting the said shaft to rise as the worm wheel is rotated on its eccentric axis.

As a result of the construction described, it will be understood that due to the eccentric mounting of the worm wheel, the rotation thereof will be imparted to the driven shaft 16 at variable speed, from a maximum speed when the worm is nearest the axis of the worm wheel, to a minimum speed when the worm is at its greatest distance from the worm wheel, so that at a certain period in the rotation of the worm wheel, the mo-

tion of the driving shaft 16 is accelerated, the purpose of which will presently appear.

The driven shaft 16 has fixed to it a collar 25 provided with a hole in which extends a rod 26 held fixedly in place in the collar by a set pin 27, which rod extends at right angles to the shaft and constitutes a carrier for the dipper 2, before referred to, and which carrier, in the rotation of the shaft, will be revolved in a vertical plane about the axis thereof.

The dipper is in the present instance in the form of a cup provided near its open end and at diametrically opposite points, with aligned bearing holes which loosely receive a lateral journal arm 28 on the end of the rod 26, whereby the cup is supported by its carrier so that it may rock relatively thereto about an axis parallel to the driven shaft 16, collars 29 being fixed to the journal arm at opposite sides of the cup to confine the same thereon. In the revolution of the cup by the rotation of the driven shaft, it will by gravity assume an upright receiving position, and will be carried downwardly and immersed into the stream of "white water" flowing through the conduit beneath, and becoming filled with the "white water", the cup will be elevated by the continued movement of its carrier.

Means are provided for causing the automatic discharge of the contents of the cup when elevated, so that successive samples of the water taken from the stream in the successive cycles of operation of the cup, may be mixed together. To accomplish this object, the cup has fixed to it at one side, a finger 30 in position to engage a fixed stop arm 31 extending laterally inwardly from a vertical rod 32 extending upwardly from the longitudinal frame bar, the said stop arm being arranged in the path of movement of the finger as the cup is carried upwardly and reaches the highest point of its travel. When the finger engages the stop arm, the continued movement of the cup by its carrier will cause the cup to rock on its journal on the carrier to discharging position, as shown by dotted lines in Fig. 2, whereby the contents of the cup will be discharged into a trough 33 supported by the frame of the machine, and leading to a suitable receptacle or pail 34 at the side of the frame. As the cup continues on its way, the finger will be disengaged from the stop arm, whereupon the cup will right itself by gravity ready to receive another charge of water as it is again lowered to the flowing water.

The relation of the cup to the eccentric worm wheel and worm is such that the cup will be at the lowest point in its path of revolution, when the worm is nearest to the axis of the wheel, the result being that the speed of revolution of the cup will be accel-

erated as the cup passes through the water, and with a flow of water of approximately 104 feet per minute, which is a fair average of the flow from a paper making machine, the complete revolution of the cup will consume about eight minutes, and its immersed passage through the water will occupy about eight or ten seconds. With the cup passing through the water at this speed, it has been found that there will be little or no opportunity for the settling in the cup of the fiber or other matters held in suspension in the flowing water, hence the sample taken at any one time will be representative with respect to the proportion of suspended matters in the body of water at the time the sample is taken. In this way the mixed samples will present a true and accurate average of the condition of the "white water" flowing by during the sampling period.

While the invention has been described with particular reference to its employment in taking samples of the "white water" flowing from paper making machines, containing as it does matters held in suspension, it is not intended that the invention be limited to such use, as it is applicable as well for taking samples of other liquids containing matter held in suspension, for instance "screen rejections", and the invention is applicable also for taking samples of other liquids in which solid matter is held in suspension.

In the use of the sampling machine in connection with paper making machines, it is perhaps preferable to operate the driving member or water wheel by the flow of the liquid to be sampled, so that these samples will be taken in frequency, dependent upon the rate of said flow. But good results can be obtained by operating the driving member by means independent of the liquid being sampled, in which case the water wheel may be supported free of said liquid, and may be operated by a water jet impinging upon the wheel, or by other independent operating means.

I do not claim broadly herein the movement of the sampling dipper through the liquid to be sampled at such speed as to prevent the undue settling of the suspended matter, as this is claimed both as to the method of operation and the apparatus, in broad terms in my co-pending application filed August 2nd, 1929, Serial No. 383,076. The present application is limited to mechanism by which the dipper is accelerated in its movement in such manner that for a portion of its movement it will advance at a given speed, and at another portion, that where it passes through the liquid, the motion is accelerated so as to be rapid. The present application is therefore limited to a specific means for accomplishing the result

claimed broadly in my said copending application above referred to.

In the foregoing description and accompanying drawings, the invention has been set forth in the particular detailed form and arrangement of the parts which in practice have been found to answer to a satisfactory degree the ends to be attained. It will be understood however, that these details may be variously changed and modified by the skilled mechanic without departing from the limits of the invention, and further, it will be understood that the invention is not limited to any particular form or construction of the parts, except in so far as such limitations are specified in the claims.

Having thus described my invention, what I claim is:—

1. In a sampler for materials, the combination of a driving member, a dipper movable through the material to take samples of the same, and movable from the material to elevate said samples, and connecting gearing between said driving member and dipper to accelerate the motion of the dipper when passing through the material.

2. In a sampler for materials, the combination of a driving member, a revoluble dipper movable at one part of its revolution through the material to take samples of the same, and connecting gearing between the driving member and dipper to accelerate the motion of the dipper when passing through said material.

3. In a sampler for materials, the combination of a rotary driving member, a rotary driven member, a sampling dipper revolved by said driven member to pass through the material to take samples thereof, and means for accelerating the motion of the driven member at a given point in its rotation.

4. In a sampler for materials, the combination of a rotary driving member, an eccentrically mounted gear wheel, a power transmitting shaft geared to the driving member and to the gear wheel to move the latter with accelerated motion at a given point in its rotation, and a sampling dipper operatively connected with the eccentric gear wheel to be rotated thereby.

5. In a sampler for materials, the combination of a rotary driving member, an eccentrically mounted worm wheel, a power transmitting shaft geared to the driving member, a worm on said shaft in mesh with the worm wheel, said shaft being movable to and from the axis of the worm wheel to maintain the worm in mesh with the worm wheel, and a sampling dipper operatively connected with the worm wheel to be revolved thereby.

6. In a sampler for materials, the combination of a frame, a rotary driving mem-

ber journaled therein, a transverse driven shaft journaled in the frame, a worm wheel mounted eccentrically on said shaft, a longitudinally extending up and down movable power transmitting shaft geared to said driving member, a worm on said shaft in mesh with the worm wheel, a spring acting on the power transmitting shaft to maintain the engagement of the worm with the worm wheel, and a sampling dipper carried by the driven shaft to be revolved thereby.

In testimony whereof, this specification has been duly signed by:

CHARLES F. RHODES.
